UNITED STATES PATENT OFFICE.

EDWARD T. BETKER, OF KANSAS CITY, MISSOURI, ASSIGNOR TO BROOKING T. HICKMAN,
OF KANSAS CITY, MISSOURI.

PRESSING-MACHINE.

1,250,420.

Specification of Letters Patent. Patented Dec. 18, 1917.

Application filed June 12, 1916. Serial No. 103,288.

To all whom it may concern:

Be it known that I, EDWARD T. BETKER, a citizen of the United States, residing at Kansas City, in the county of Jackson and State of Missouri, have invented certain new and useful Improvements in Pressing-Machines, of which the following is a specification.

My invention relates to steam pressing machines for pressing garments, clothes, etc., and one object of the invention is to provide novel means whereby the pressure of the pressing members is equally distributed over the article being pressed.

15 A further object is to provide novel means whereby the degree of pressure exerted upon the articles being pressed can be regulated at the will of the operator and at a minimum expenditure of labor.

20 A further object is to provide means whereby the degree of heat and rapidity of circulation of the steam employed for heating the pressing members of the machine can be regulated at will.

25 Other objects will hereinafter appear, and in order that said invention may be fully understood, reference will now be made to the accompanying drawings, in which:

30 Figure 1 is a side elevation of the machine with its presser head in raised position.

Fig. 2 is a front elevation of the machine with the presser head in lowered position.

35 Fig. 3 is a plan view of the machine with the parts in the position disclosed by Fig. 2.

Fig. 4 is a broken plan view of the presser head.

Fig. 5 is a longitudinal section of the 40 presser head on line V—V of Fig. 4.

Fig. 6 is a broken plan view of the bed of the machine.

Fig. 7 is a longitudinal section on line VII—VII of Fig. 6.

45 Fig. 8 is an enlarged sectional view of a swivel joint employed in carrying out the invention.

Fig. 9 is a vertical section of a boiler constituting a part of the machine.

50 1 designates the pedestal of the machine upon which a table 2 is mounted to hold the garments or cloth to be pressed.

3 designates a steam bed provided with a

hollow standard 4 secured upon the table 2. The top plate 5 of the bed 3 has perforations 6 for the passage of steam therethrough and is covered with a cushion 7 of felt or other suitable material.

55 8 designates the presser head which coats with the bed 3 in pressing cloth and garments. Said presser head 8 has an internal steam chest 9 spaced from the top and bottom plates 10 and 11 to form chambers 12 and 13, respectively, which communicate with each other through ports 14 surrounding screws 14^a, whereby the steam chest 9 and the plates 10 and 11 are secured together. The ports 14 permit heat radiated from the top of the steam chest 9 to pass from the chamber 12 down into the chamber 13, and on commingling with the steam in the latter escape through the perforations 15 in the bottom plate 11.

60 The bottom plate 11 is covered with a cushion 11^a to coat with the cushion 7 on the bed 3 in equalizing the pressure over the entire surface of the cloth placed upon said bed. The cushion 11^a is held in place by any suitable means. In the drawings, I have shown for this purpose a clamp 16 held in place by stud bolts 17 and thumb nuts 18, which permit easy removal of said cushion 11^a when desired. Bolts 17^a, are provided for connecting the two members of the clamp together.

65 85 The top of the presser head 8 is provided with a pair of bearings 19 in which a rock shaft 20 is mounted carrying a handle 21, whereby said presser head 8 is lowered upon the bed 3. The shaft 20 is also mounted in a rock arm 22, which in turn is mounted upon a stationary shaft 23 mounted in a bearing 24, secured to the upper portion of the pedestal 1. The ends of the shaft 23 are provided with rigidly mounted fittings 90 25, for a purpose which will hereinafter appear.

95 In order that the rock arm 22 may exert considerable downward pressure upon the presser head 8 when the same is lowered to the steam bed 3, and yet allow said presser head to accommodate itself to any inequalities in the thickness of the cloth placed upon said bed 3, I provide the upper side of said presser head 8 with three screws 26, 100 105 extending through openings in the rock arm

23 and encircled by springs 27, bearing upon said rock arm 23. Two of the screws 26 are disposed at the rear of the rock shaft 20, while the other is at the front of said rock shaft, as disclosed by Figs. 1 and 3.

5 The rear end of the rock arm 22 is pivotally secured to a connecting bar 28 pivotally secured at its lower end to a link 29, which in turn is pivotally connected to a 10 lug 30 extending rearwardly from the pedestal 1. A counterweight 31 is secured to the connecting bar 28 to normally hold the presser head 8 in raised position (Fig. 1).

32 designates a treadle whereby extra 15 pressure is applied to the presser head 8 after the same has been lowered into contact with a garment upon the bed 3. Said treadle is fulcrumed to the pedestal 1 at 33 and provided at its rear end with a counter- 20 weight 34 to normally hold the forward end of said treadle 32 in raised position. The link 29 and the upwardly curved rear end of the treadle 32 are so disposed with relation to each other that when the former is 25 raised by the lowering of the presser head 8 it will pass slightly above the lower edge of the inclined terminal 35 of the treadle, so that when the same is actuated said inclined terminal contacts and pushes the arm 30 29 upward and thus imparts the desired pressure to the presser head 8.

36 designates a boiler for supplying the bed 3 and the presser head 8 with steam. Dry steam is conducted from said boiler 36 35 to the bed 3 through a pipe 38 and a pipe 40, which latter extends upwardly through the hollow standard 4 and terminates in an open T-head 41, located in the bed 3, so that the discharged steam may pass out 40 through the perforations 6. The flow of steam through the pipe 38 is controlled by a valve 42 within easy reach of the operator standing at the table 2.

43 designates a steam jet to exhaust condensed steam from the bed 3 through the pipe 40 and a communicating exhaust pipe 44. The jet 43 receives its steam from the pipe 38 with which it communicates through a T-coupling 45, and is provided with a 45 valve 46 for cutting off the flow of steam therethrough.

In addition to heating the steam bed 3 by steam discharged from the T-head 41, said bed is heated by steam radiated from a coil 55 47, the two legs 48 and 49 of which pass through the hollow standard 4. The leg 48 receives steam from the pipe 38 with which it communicates through a T-coupling 50, and the leg 49 communicates with a return 60 pipe 51, which conducts the steam back into the lower portion of the boiler 36. A drain cock 52 is connected to the lower portion of the leg 49 to exhaust steam therefrom and thus cause the steam to circulate more rapidly and heat the coil 47 to a higher degree 65

than when the steam is permitted to return to the boiler through the pipe 51. Communication between the steam bed 3 and the neck 4 is closed by a plate 40^a, from which a drain pipe 40^b depends to carry off condensed steam from said bed 3.

70 Steam is conducted from the boiler 36 to the steam chest 9 of the presser-head 8 through pipes 53 and 54, and returns from said steam chest to the boiler through return pipes 55 and 56, and an injector 57 which communicates with said pipe 56 through a T-coupling 58. The injector 57 receives its steam from the boiler through a pipe 59 and the pipe 38 which communicates through a 80 T-coupling 60. The pipes 53 and 56 have rigid connections with the respective fittings 25, while the pipes 54 and 55 are swiveled to said fittings, so that the last-mentioned pipes may rock with the arm 22 when the presser- 85 head 8 is raised and lowered.

Steam is admitted to the lower chamber 13 of the presser-head 8 through a pipe 63, which communicates with the pipe 54 and is provided with a valve 64 to control the 90 flow of steam therethrough. The flow of steam through said pipes 63 is further controlled by a self-closing valve 65, embodying a lever 66 pivoted to a push rod 67, extending through the handle 21 and provided 95 with a knob 67^a which can be readily operated by the hand grasping said handle 21.

The boiler 36 has a superheating steam coil 68 in its upper portion communicating with the pipes 38 and 53. A tank 69 is employed to provide a supply of feed water to the boiler with which it is connected by pipes 70 and 71. Pipe 70 leads from the upper part of a steam chamber 72 to the upper portion of the tank 69 to heat the 105 water therein and also to force water into the boiler through the pipe 71, which has a valve 73 and a check valve 74, which latter cuts off back pressure from the boiler. The pipe 70 is provided with a valve 75 to control the flow of steam therefrom.

The tank 69 may be supplied from any suitable source, or it may be filled through a valve 76 at its upper end. As, approximately, all of the condensed steam is returned to the boiler 36, very little water need be drawn from the tank 69. Heat for generating steam is applied through a suitable burner 77, placed beneath the boiler 36.

The heat from the burner circulates upwardly past water tubes 78 in the lower portion of the boiler, thence through a flue 79, and escapes from the superheating chamber 80 of the boiler through a stack 81.

From the foregoing description, it is apparent that I have produced a machine embodying all of the advantages above enumerated, and while I have shown and described the preferred construction, combination, and arrangement of parts, I do not restrict my 125 130

self thereto but reserve the right to make such changes as properly fall within the spirit and scope of the claims.

Having thus described my invention, what I claim and desire to secure by Letters Patent, is:

1. In a machine of the character described, a bed to support articles to be pressed, a presser-head, means operably-supporting said presser-head, a link connected to said means, and a treadle having a surface to engage said link and exert extra pressure on the presser-head when the same is lowered to the bed and the treadle is forced down-
wardly.

2. In a machine of the character described, a bed to support articles to be pressed, a presser-head to coact with said bed, a rock-arm upon which said presser-head is mounted, a pivotally-mounted link, a connecting-bar, operably-uniting said rock-arm and the link, a counterweight on the connecting-bar to normally hold the presser-head in raised position, and a treadle having a surface to engage the link and exert extra pressure on the presser-head when the same is lowered to the bed and the treadle is depressed.

3. In a machine of the character described, a bed to support articles to be pressed, means 30 for introducing steam into said bed, a presser-head, to coact with said bed, means operably-supporting said presser head, a pivotally-mounted link connected to said means, and a treadle having a beveled surface to engage said link and exert extra pressure on the presser-head when the same is lowered to the bed and the treadle is de-pressed.

4. In a machine of the character described, 40 a bed to support articles to be pressed, a presser-head operably-mounted to coöperate with said bed, a handle to lower said presser-head upon the bed, a pipe for conducting steam to the presser head, a self-closing 45 valve for cutting off the flow of steam through said pipe, a lever for opening said valve, and a rod extending through the presser-head handle and connected to said lever to actuate the same.

In testimony whereof I affix my signature, in the presence of two witnesses.

EDWARD T. BETKER.
